HIGH VACUUM PUMP

Kenneth C. D. Hickman, Rochester, N. Y., assignor, by mesne assignments, to Distillation Products, Inc., Rochester, N. Y., a corporation of Delaware

Application May 18, 1937, Serial No. 143,305

11 Claims. (Cl. 230—101)

This invention relates to improvements in high vacuum or condensation pumps and, particularly, to condensation pumps adapted to employ mixed organic pumping fluids.

5 In my co-pending application No. 27,652, filed June 21, 1935, of which this is a continuation-in-part, there is disclosed improved forms of condensation pumps. It was disclosed therein that organic pump fluids are mixtures of substances 10 of different vapor pressure and that volatile or very non-volatile constituents are present which undesirably affect the pumping action of the useful components of the pump liquid. It was further disclosed that the pump liquid could be segregated into useful and non-useful pumping components and that the useful components could be further segregated into portions of progressively decreasing volatility and caused to perform 15 their pumping action at appropriate positions in a cascade pump.

It is an object of this invention to provide improved fractionating pumps of the character described. A further object is to provide improved condensation pumps adapted to employ mixed 20 organic pumping fluids, the constituents of which have differing vapor pressures. Another object is to provide improved fractionating condensation pumps of high efficiency and/or pumping capacity. Another object is to provide fractionating condensation pumps having greater simplicity and ease of construction and operation. Other objects will become apparent from the following description.

My invention will be more clearly understood 35 from the following description and the accompanying drawings wherein I have illustrated several embodiments thereof, wherein like numerals refer to like parts, and wherein:

Fig. 1 illustrates a sectional elevation of one 40 of the forms of fractionating pumps embodying the principles of my invention and having the advantage of utmost in simplicity of construction due to the use of cylindrical elements;

Fig. 2 is a section taken on line 2—2 of Fig. 1;

Fig. 3 is a sectional elevation of a modification 45 of the apparatus illustrated in Fig. 1;

Fig. 4 is a sectional view taken on line 4—4 of Fig. 3;

Fig. 5 is a sectional elevation of a preferred 50 form of condensation pump;

Fig. 6 is a sectional view of the pump of Fig. 5 taken on line 6—6;

Fig. 7 is a sectional view taken on line 7—7 of 55 Fig. 5;

Fig. 8 is a sectional fragmentary view taken on line 8—8 of Fig. 5;

Fig. 9 is a fragmentary sectional elevation of a modification of the high vacuum jet system in Fig. 5;

Fig. 10 is a sectional elevation of a pump similar to that illustrated in Fig. 3 but provided with fractionating trays in the low vacuum end for segregation of volatile components;

Fig. 11 is a sectional view taken on line 11—11 of Fig. 10;

Fig. 12 is a sectional elevation of a conventional condensation pump provided with fractionating features and a flash boiler, and arranged to work in conjunction with a cascade fractionating 15 condensation pump;

Fig. 13 is a modification of the apparatus illustrated, a flash boiler centrally located in the jet system being provided;

Fig. 14 is a sectional view on line 14—14 of Fig. 13.

Referring to Figs. 1 and 2, reference number 3 designates an approximately cylindrical main pump casing attached to a flange 4 at the low pressure end and integral with a plate 5 at the 25 high pressure end, which plate is connected to a conduit 6 leading to a backing pump (not shown). Numeral 7 designates a conduit detachably connected to flange 4 and which connects pump casing 3 with the receptacle or system to be evacuated. Numeral 16 designates a plurality of half moon-shaped plates integral with the base of conduit 6 and which serve to fractionate and segregate the most volatile components of the pump 30 fluid, which may be intermittently withdrawn 35 by way of conduit 17.

Numeral 8 designates an approximately cylindrical casing located inside the main casing 3 and split at the base to form two supporting ribs 9 and 10 which rest upon the bottom of main casing 3 and serve to support casing 8 and partition the space inside casing 8 from the annular space formed between the outside of casing 8 and the inside of casing 3. The portion of casing 8 located in the high vacuum end of the pump is 40 constricted to form a circular opening 11 which is covered by an umbrella type of jet 12. At spaced intervals within casing 8 are located a series of partitions 13, 14 and 15 which are integral with the walls of casing 8 and with supporting members 9 and 10 and which extend to the base of main casing 3 and divide casing 8 45 into a series of compartments A, B, C and D. In the base of compartments B and C are located a plurality of staggered baffles 18 which serve to 50 55

delay the flow of fluid therethru. The low vacuum end of casing 8 is closed by an integral partition 20 which also forms an approximately gas-tight connection with plate 5 by means of extension 21.

5 A plurality of approximately annular jets 22, 23 and 24 are formed by conical flanges 26, 27 and 28 concentric and integral with casing 8 and which terminate at the supporting members 9. Reference numerals 29, 30 and 31 designate series of openings in the wall of casing 8 located under the jet formed by flanges 26, 27 and 28, respectively, and preferably are of decreasing diameter from the low to the high vacuum side of the pump, as shown. Reference numeral 32 designates a body of pumping fluid which rests in the base of the main casing 3 and is divided into a plurality of separate pools of fluid by partitions 13, 14 and 15. The partitions are provided with 10 a series of notches 33, 34 and 35 at the base, which allow flow of liquid from one compartment to another, but which substantially prevent the flow of vapor from one section or compartment to another. The level of the liquid in the various 15 compartments can be controlled by raising or lowering the high vacuum end of the pump by means of adjusting element 40, and the liquid in each compartment is heated by a heating element 41 which is thoroughly lagged with insulating material 42. Heating element 41 is preferably 20 divided into a number of sections so that the temperature in the boiler of each compartment, A, B, C and D can be separately controlled. Numeral 43 designates a casing substantially concentric with main pump casing 3 and fastened to plate 5 and flange 4. Casing 43 serves as a jacket for the circulation of cooling fluid into contact with the main pump casing during operation of the pump. Fluid is circulated by introduction 25 through conduits (not shown) located at the low and high vacuum ends thereof.

Referring to Figs. 3 and 4, numeral 53 designates a main pump casing having a cylindrical upper portion and a flattened base which serves 30 as a reservoir for pumping fluid 32. The high vacuum end of casing 53 is connected to a flange 4 which is in turn connected to conduit 7 leading to the chamber to be evacuated and which is provided with fractionating rings 52. The base 35 of 53 at the high vacuum end is raised at 55 as shown, to form a dam for the pump fluid in the reservoir. An element 57 having the form of a section of a cone is split at the base to form supporting ribs 9 and 10 and is located inside the main casing 53 and integral therewith. The taper of section 57 is such that the distance 40 between it and the walls of section 53 is smaller at the low vacuum, than at the high vacuum end in order to form jets 26, 27 and 28 of progressively increasing area in accordance with approved condensation pump jet practice. The low vacuum end of internal casing 57 is closed 45 by plates 20 and 21 which are integral with end plate 5 which closes the low vacuum end of casing 53 and to which is connected the conduit 6 leading to the backing pump.

Referring to Figs. 5, 6, 7 and 8 numeral 60 50 designates a main pump casing which is slightly conical in shape, the narrower end being located at the low vacuum side of the pump. The base 55 of 60 from the high vacuum zone to the low vacuum zone is cut away and extended to form an elongated reservoir 62 having walls 63 and 64 and base 65. The approximately cylindrical element 8 has its base cut away in a position

corresponding to the location of reservoir 62 and is separated into a plurality of compartments by partitions 13, 14 and 15 which extend to the base 65 of reservoir 62 as shown. The bottom edges of partitions 13 and 15 are provided with a series of openings 33 and 35, but the bottom edge of partition 14 extends to the base plate 65 of the reservoir and may be integral therewith. The base of cylindrical casing 8 is provided with two supporting extensions 66 which are integral with the lower portions of partitions 13, 14 and 15 and which are separated from the walls 63 and 64 of the reservoir 62 by spacers 68 which are preferably thicker at the upper than at the lower end so that a wedge-shaped space exists between the walls 63 and 64 of the reservoir and of the supporting extensions 66. The bottom edges of supporting members 66 are provided with a series of nicks or openings 69 so that the wedge-shaped space is connected to reservoir 62. Plate 14 extends to the base plate 65 of the reservoir 62 and substantially prevents the flow of liquid from the boiler of B to that of C. The base of partitions 14 and 15 are restricted to form a clear passageway 80 from the reservoir of compartment B to that of compartment D. A plate 70 integral with the restricted ends of 14 and 15 serves to separate compartment C and its reservoir portion from the passageway 80.

The high vacuum end of casing 8 is constricted to form a circular opening 73 of small diameter which is capped by element 71 to form the jet 72. It will be noted that the restricted throat 73 is formed so that the jet 72 has a greater diameter. A series of baffles 74 and 75 are located in the high vacuum end of casing 60 and near the base of baffles 75 is located a conduit 76. The low vacuum end of the pump casing 60 is connected to and integral with a flange 77 which is connected to conduit 6 which leads to a backing pump. A packed adjustment screw 81, which is also sealed in oil, by a sealing liquid introduced through cup 82, is connected to plate 78 by integral unit 83 and permits one to slide 40 the assembly 8 back and forth to obtain the proper jet clearances between 8 and conical casing 60.

Referring to Fig. 9, numerals 86 and 87 designate the wall and cap of an umbrella type jet, 50 72, the vapor for operation of which is supplied by conduit 88 which is flared at 89 and integral with the wall of 86, and which connects with rectangular box-like extension 90 as illustrated. The walls 91 and 92 of 90 extend into the pump 55 fluid reservoir, and separate the boiler into a compartment in substantially the same way as partitions 14 and 15 of Fig. 1 separate the boiler into an individual compartment. The compartment thus segregated is analogous to compartment C in the other figures and is so labeled. The bottom edges of walls 91 and 92 extend to the base of the boiler and are provided with holes 93 and 94 in order to allow passage of 60 pump liquid from the boiler of compartment B 65 into section 90 and thence into the reservoir of compartment D. The reservoir in section D communicates with the openings 31 in the pump section 8, so that vapors travel therefrom through the openings and into the jet 72.

Referring to Figs. 10 and 11 numeral 3 designates an approximately cylindrical pump casing provided with internal casing 8 substantially the same as that illustrated in Fig. 1 and being provided with partitions 20, 13, 14, 15, separating 70 75

the boiler and pump into separate compartments which deliver vapors to separate jets 26, 27 and 28. Partition 20 is provided with openings 106 at the base thereof, and main pump casing 3 is extended at the low vacuum end to form a chamber 107 closed by plate 5 which is connected with conduit 6 leading to the backing pump. The boiler in the base of chamber 107 is divided into sections by partitions 108 and 109 which are slightly elevated from the base to allow free flow of liquid from one section to another but prevent substantial turbulence thereof. Along the walls of chamber 107 are located a plurality of trays 110 which are closed at one end by plates 111 and are integral with plate 5 at the other end.

In Fig. 12, reference numeral 128 designates a cylindrical main pump casing in the base of which is located a reservoir 129 and a body of pump fluid 32 as in Fig. 1. Partitions 13, 14 and 15 are located in the internal casing 8 substantially as previously described and serve to separate the boiler or reservoir into compartments and deliver separate vapor streams to the individual jets 26, 27 and 28 by way of openings 29, 30, and 31. The low vacuum end of casing 8 is closed by partition 20 which extends to the base of main pump casing 128, and is provided with openings 130 along the bottom edge thereof. Main pump casing 128 is connected at the low vacuum end to the intake alembic 134 of a conventional condensation pump consisting of a jet 135, condenser 136 and boiler 137. The condenser 136 is also provided with a series of re-entrant or fractionating trays 138 which terminate in a conduit 139 which leads to a backing pump. The intake alembic 134 and the boiler 137 are connected by conduits 140 and 141 to a pumping liquid reservoir 142. Pumping compartment C in casing 128 is connected with the base of reservoir 142 by conduit 143 which is provided with a drop counter 144.

In Fig. 13, numeral 148 designates a cylindrical conduit bent at right angles to form an extension 149 at one end and extension 150 at the other end. Section 150 is provided with a series of fractionating trays 151 which connect to a conduit 152 which is, in turn, connected to a backing pump (not shown). In the walls of section 149 are formed a series of trays 153, the lower one of which connects to a conduit 154 communicating with a reservoir 155. Reservoir 155 is partially filled with pump fluid 32, which may be introduced through conduit 157 provided with valve 158. The base of reservoir 155 connects to conduit 159 in which is located a magnetically operated pump plunger 160, provided with a central opening 161, closed by valve ball 162. Above the plunger is located a ball valve 164. The upward thrust of the plunger is caused by the intermittent actuation of solenoid 163 and the liquid forced upward by each thrust is prevented from flowing backwards by ball valve 164. Conduit 165 delivers pump liquid into boiler tray 166 and conduit 167 serves to deliver fluid flowing from boiler 166 into trays 153 in the walls of section 149. Conduit 167 is provided with a spiraled section which is jacketed by 168 through which cooling fluid is circulated by way of conduits 169 and 170. Boiler 166 is located centrally within a series of cones 175, 176, 177 and 178. Cone 178 is provided with a closed base 171 which is integral with the bottom of boiler 166. A plate 179 having a flared edge 180 is integral with the boiler at the position shown and is provided along

the inside edge with a series of openings 181 which allow the flow of pump liquid therethrough but which substantially prevent the escape of vapor generated inside the boiler. Boiler 166 is provided with a heating element 182 along its base, including the portion 183 projecting outside the portion covered by the cones.

In operation employing the apparatus of Fig. 1, pump fluid is introduced to approximately to the level indicated and screw 40 is adjusted so that the liquid is at a suitable level in each of the compartments. Conduit 7 is connected to the chamber to be evacuated, and conduit 6 is connected to the backing pump which is put into operation. When the pressure in the system has been lowered sufficient by backing pump, usually to less than about .1 mm., the heating element 41 is put into operation and the liquid gently heated to vaporizing temperature. With new pump fluid degassing may require a considerable period of time, but if the pump has previously been in operation, pumping action will begin immediately. Vapors generated in compartment A travel upward through the holes 29 in casing 8 and are deflected by jet cover 26 in the direction of the backing pump. The same action takes place in compartments B, C and D. Vapors passing through mushroom jet 12 entrain gas diffusing from the chamber to be evacuated through conduit 7 and force them into the vapor jet issuing from 24. Vapors from jet 12 are condensed upon the inside wall of main casing 3 and flow thence down into the boiler in the base of the casing, passing between the wedge-shaped passage formed between supporting extensions 10 and the inside walls of 3. Vapors issuing from jet 24 force gases pumped from jet 12 to jet 23 and then condense in a similar manner on the inside walls of casing 3 in the neighborhood of the jet and pass down the walls back into the boiler of section C. Similar action takes place with the vapors issuing from the jets 23 and 22.

During the operation of the pump, higher vapor pressure pump vapors will tend to persist for a longer time before condensing on the walls of 3, while the lower vapor pressure pump vapors will condense almost immediately and will directly return to the boiler compartment from which they came. The lighter vapors will tend to pass into the next jet before condensation and there will, therefore, be a tendency for the pump to thrust light or high vapor pressure constituents towards the low vacuum end of the pump or into compartment A, while the successively lower vapor pressure constituents will immediately condense and return to the original boiler and thus become segregated successively in compartments B, C and D. A similar fractionating effect takes place in the boiler. Light constituents are vaporized and pass through the jet, 22. The unvaporized less volatile constituents pass through the openings 33 into section B where the next lower vapor pressure constituents are vaporized and pass through jet 23. The remaining constituents pass through openings 34 into compartment C where the next lowest vapor pressure constituents are removed and pass through jet 24. The lowest vapor pressure constituents of the pump fluid are therefore vaporized in compartment D and exert their effect in the jet 12 which operates under the highest vacuum and they are, therefore, employed at the point where a low vapor pressure pump fluid free of undesirable lighter constituents can perform the best pumping action. By

thus separating the pump fluid into constituents of progressively decreasing vapor pressure and causing each constituent to operate at its appropriate pressure, the higher vapor pressure portions are caused to do most of the pumping at the higher pressure, while the lower vapor pressure fractions are allowed to simmer gently at the high vacuum end where they reduce the residual gas pressure to a very low value. Heater 41 is preferably separated into a number of sections, the temperatures of which can be independently regulated so that the appropriate temperature for vaporizing the several pump fluid constituents can be properly selected. The fractional condensation and separate return of condensate is decidedly advantageous, but pumps in which all condensate is returned to the first compartment or is otherwise mixed and returned to the boiler are considered as part of my invention if they embody the features of jet and boiler arrangement and design herein disclosed.

The staggered baffles 18 shown in the base of the boiler of Fig. 1, smooth the flow of pumping liquid and assure vaporization of desired components before it reaches the next vaporizing compartment. Such baffles can be employed with advantage in the apparatus illustrated in the other figures.

The apparatus illustrated in Figs. 3 and 4 is operated in somewhat the same manner as that of Fig. 1. The boiler, however, is substantially horizontal and is not shown as being subject to regulation by tilting. The flow of liquid from compartment A to co compartment C takes place in substantially the same manner and the tilting mechanism, while advantageous for fine adjustment, is unnecessary. The internal casing 57 is shown as being restricted so that it is somewhat conical and the distance between jet 28 and wall 53 is greater than the distance between jet 26 and wall 53. In this way the clearance of the jets increase progressively from the low to the high vacuum side of the pump and the efficiency is therefore increased. The pump illustrated in these figures is devoid of a jet extended into the high vacuum end as was shown in Fig. 1. The use of such a jet is preferred since it is completely circular and enables ejection of gases on all sides of the jet operating under the highest vacuum. The features of this pump can be combined with the extended jet if desired. The casing 53 is shown unjacketed, however, jacketing is advantageous in some cases and may be employed if desired.

In operating the apparatus of Figs. 5-8, conduit 7 is connected with the chamber to be evacuated and conduit 6 to a backing pump, which is started and the system evacuated to a sufficiently low value, at which time pump fluid in the reservoir 62 is heated by a heating element (not shown). The lighter components of the pump fluid are vaporized in the boiler section A between partitions 20 and 13. The vapors pass from the boiler up into the cylindrical space between these two partitions, and out through openings 29 and are deflected as a vigorous vapor stream towards the low pressure end of the pump by jet 26. The pump fluid deprived of its more volatile constituents flows through the openings 33 in the bottom edge of partition 13 into the boiler compartment at the base of section B. Vaporization of the next volatile constituents takes place which pass out by way of openings 30 and jet 27. The pump fluid then flows through by-pass space 80 formed by the base 65 of the boiler and walls 67 and 70

and passes into the boiler of section D. The liquid, therefore, by-passes section C and goes directly from the boiler of section B into the boiler of section D. In the boiler of section D vaporization of the best portion of the pump fluid takes place and the advantages of its pumping action availed of in the high vacuum jet 12. The pump fluid deprived of these constituents then passes through the openings 35 in the bottom edge of partition 15 into the boiler under section C. Here vaporization of the least volatile constituents takes place and they pass out through openings 13 and jet 24. The boiler under section C serves as a sump for the non-volatile constituents of the pump fluid. The jet operating under the highest vacuum is thus supplied with the best portion of the pump fluid, which is substantially free of non-volatiles, while that containing the non-volatile constituents, as well as useful low vapor pressure pumping constituents is employed in the next highest pressure jet.

The fractionating effect exerted by the condensing walls of main casing 60, further aids in the separation of the constituents of the fluid as explained in connection with Fig. 1. Condensate 25 flows down the walls of 60 into the wedge-shaped space between walls 64 and supports 66 and thence back into the boiler 62. During operation some of the pump fluid vapors may tend to diffuse backwards towards the chamber being evacuated. The two series of baffles 74 and 75 serve to condense such vapors. Those condensing in baffles 74 flow along the bottom of 60 and pass back into the boiler at the base of compartment D. Those condensed by baffle 75 flow to the base thereof and are withdrawn through conduit 76.

In Fig. 9 is illustrated a modification of compartments C and D illustrated in Fig. 5. The last jet 72 is supplied by vapor from compartment C. The vapors travel from the boiler of compartment C up through conduit 88 and are ejected through jet 72. The entire conduit 88 is surrounded and warmed by vapors from the boiler of compartment D which supplies compartment D and jet 28. The vapors from jet 72 are the lowest vapor pressure constituents of the pump fluid and, therefore, have a decidedly greater tendency to condense before reaching the jet even at somewhat elevated temperatures. Since the conduit supplying the jet 72 is entirely surrounded by vapors from the boiler supplying compartment D, the lowest vapor pressure pumping vapors are substantially prevented from condensing before reaching the jet 72.

In operating the apparatus illustrated in Fig. 10, pumping fluid is introduced into the boiler compartments to approximately the level indicated. The high vacuum end of the pump is connected to the chamber to be evacuated and conduit 6 is connected to the backing pump which is put into operation. Pump fluid is heated by the element 41 and is partially vaporized in compartment 101. Light, or high vapor pressure constituents, are vaporized and tend to condense in the fractionating trays 110. Fractionation of the vaporized pump fluid takes place in these trays and the lower vapor pressure constituents are returned to the boiler. The pump fluid, deprived of these undesirable constituents which have too high a vapor pressure for useful pumping, then passes through openings 106 in the bottom edge of partition 20. In compartment A the lightest useful constituents are vaporized and pass out through jet 26. The successively lower vapor pressure

constituents are then vaporized in compartments B and C as the fluid passes successively therethrough as explained above. The fractionating trays 110 enable the use of a pump fluid which has not been refined to remove any or all of the lighter constituents which would have an adverse effect on the pumping action of jets 26, 27 and 28. The operation of jets 26, 27 and 28 of Fig. 12 is substantially the same as described in connection with the apparatus illustrated in Figs. 1 and 3. The high vacuum end of 128 is connected to the system to be evacuated and conduit 139 is connected to a backing pump and the entire system is evacuated to a low pressure at which the condensation pump can operate. The pumping fluid in boilers 137 and 129 is then heated by heating means (not shown). Vapor from the boiler of compartment C passes through openings 31 and issues through jet 28 entraining gases diffusing from the chamber to be evacuated. Condensate from the walls of 128 flow back into the boiler. The gases entrained by jet 28 are entrained in vapors from jet 27 and finally by vapors from jet 26. Vapors rising from boiler 137 pass through jet 135 and entrain gases forced into 134 by jet 26. The gases are carried with the vapor stream up into condenser 136 and are removed from the system by the backing pump connected to conduit 139. Light portions of the pumping fluid condense in the re-entrant rings 138 and are thus prevented from returning to the pumping fluid. Condensate from condenser 136 flows down the walls of 134 and passes successively through the boilers of compartments A, B and C and finally overflows into the conduit 143 and is returned to reservoir 142. Reservoir 142 holds the main supply of pump fluid and allows it to flow into boiler 137 by way of conduit 141 at a rate corresponding to that at which it is vaporized from the boiler. In this way only small amounts of the pump fluid are heated at any time and decomposition is thereby considerably decreased. Conduit 140 connects the reservoir 142 with the source of vacuum so that the pressure maintained therein will be substantially the same as that in the rest of the system.

In operating the apparatus of Fig. 13, conduit 152 is connected to the backing pump and conduit 149 to the system to be evacuated. Reservoir 155 is filled with pump fluid to approximately the level shown and the system is evacuated by the backing pump. Solenoid 163 is actuated intermittently causing the pump plunger 160 to move up and down, forcing liquid through conduit 165 into boiler 166. In the fore part 183 of the reservoir, the pump fluid is heated and freed of its most volatile constituents which pass up the conduit 150 and are condensed and retained in the fractionating trays 151 and may be removed therefrom by way of conduit 172 at appropriate intervals. The pump fluid free of volatiles then flows through the openings 181 in element 179 and is vaporized during its passage from conical jets 175 to 178. The higher vapor pressure constituents of the pump fluid pass out through the jet formed by cone 175. The next lower vapor pressure constituents pass out through jet 176, and so forth. The residue passes through opening 184 and overflows into conduit 167, is cooled to an appropriate temperature in cooler 168 and then overflows from one trough 153 to another. The liquid finally flows through conduit 154 back into reservoir 155. The purpose of washing the walls at 153 is to remove gases absorbed thereto, or to remove pump fluid which has absorbed gases dur-

ing a previous shut down. The pump fluid picks up these materials and conveys them to the low pressure side of the pump, namely to the low pressure end 183 of boiler 166, where the gases and volatiles are released and withdrawn into the backing pump and are prevented from interfering with the higher vacuum stages of the pump. The reservoir 155 permits heating of only small amounts of the pump fluid as explained in describing the apparatus of Fig. 12.

While several of the drawings illustrate pumps having an extended or projecting high vacuum jet, such as jet 12 in Fig. 1, and jet 72 in Fig. 5, it will be apparent that this same expedient can be employed with the other types of pumps illustrated, and that the use of such jets will in many cases be necessary or desirable. The extended jet illustrated in Fig. 5 is preferred, since the particular construction shown enables a higher pumping rate. Any analogous construction gives the high pumping characteristic of this type of jet as long as the walls delivering the vapor to the mushroom jet are constricted at a point immediately below the mushroom jet or, in other words, is constricted below the point at which the vapors issue from the jet. It is believed that the high pumping rate obtained by a jet constructed in this manner is due to the fact that the vapors issuing therefrom can expand both inwardly toward the axis of the tube delivering the jet vapor as well as outwardly from the cap 71. An advantage of using a jet projecting back of the main casing 8 is that vapors condensed on the walls of the main pump casing in that area will be swept by the jet vapors back into the boiler of the main pump. Such action is of considerable advantage when gases are absorbed in the pump fluid in that area during shut down of the pump.

It will be apparent that many changes and modifications can be made in the apparatus illustrated without departing from the spirit or scope of my invention. For instance, all of the internal jets can be constructed as one removable unit, as illustrated in Figs. 1 and 5, including the partitions, main casing, etc. and can be inserted inside the main pump casing. Such construction would simplify the problems of dismantling and assembling the pump when necessary for cleaning. The apparatus illustrated in Fig. 1 is most easily constructed since most of the elements are cylindrical. Also cylindrical elements would withstand the pressure of the atmosphere better than an irregularly shaped pump casing. The simplest boiler construction is shown in Fig. 1, but it has the disadvantages that considerable heat conduction between the boiler and the jets and walls of the condenser takes place. The extension of the boiler to the outside of the pump as illustrated in Fig. 5 considerably decreases this harmful conduction of heat and would, therefore, be preferred in many cases. However, the difficulties in construction are much greater. It is desirable to have the clearance between the jets and the main casing progressively increase from the low to the high vacuum side of the pump. This can be easily accomplished by either making the central casing 8 conical or by making the main casing 3 conical as illustrated in Fig. 5. If desired, either or both casings may be conical or cylindrical to obtain the desired increase in jet clearance. The use of conical elements has the desired advantage that the jet clearances can be varied during use by a simple adjustment as illustrated in Fig. 5. It will be apparent that the number of jets and compartments can be varied

and that the number illustrated has no particular significance. Also, the size and number of re-entrant rings can be varied to enable the segregation of volatiles with return of useful constituents. Any suitable construction materials such as glass or sheet or cast metals may be used.

The apparatus illustrated has the decided advantage that a mixed pumping fluid can be used and that the different vapor pressure constituents of the pump fluid are segregated and caused to perform their pumping action at an appropriate position in the pump. Non-volatile constituents are segregated and prevented from exerting harmful action upon the entire body 15 of the pump fluid. Very volatile constituents, unsuitable for pumping action are vaporized from the pump fluid, and prevented from returning thereto. The problem of employing annular jets, or jets of similar shape to the main casing, with 20 a fractionating boiler which is approximately horizontal is overcome by the construction shown. Due to the fact that such jets operating on all sides of the casing can be employed, the efficiency and capacity of the pumps are greatly increased. 25 By means of the extended rear jet, a completely annular jet is provided at the highest vacuum zone of the pump and maximum pumping action at this important place is, therefore, possible.

The apparatus illustrated furthermore is decidedly advantageous since it enables fractionation of the pump fluid vapors issuing from the jets as well as fractionation of fluid in the boiler. As explained above, vapors issuing from the lowest vapor pressure jet are more or less fractionally condensed, the lowest vapor pressure constituents immediately condensing on the walls of the pump casing and returning to the boiler compartment from which they originated. Any lighter constituents formed during the vaporization or accidentally getting into that particular 35 boiler are not condensed until they reach the next highest vapor pressure jet where they are entrained and, if of proper vapor pressure, are condensed with the vapors of that jet and returned to the boiler from which that particular 40 vapor originated. A two-fold separation and segregation of the pump fluid into constituents of progressively decreasing vapor pressure therefore takes place, and the individual constituents are 45 vaporized and caused to perform a pumping action in the most appropriate position in the pump. While this construction has obvious advantages, my invention is not limited to this 50 particular feature and it is to be understood that fractionating pumps free of such features, but 55 having jets approximately the same geometrical form as the main casing, which may be circular, elliptical or polyhydric in cross section, are contemplated as being within the scope of my invention.

What I claim is:

1. A condensation pump adapted to employ an organic pumping fluid comprising in combination, a main pump casing the longitudinal axis 65 of which is approximately horizontal, adapted to be connected at the high vacuum end to the receptacle to be evacuated and at the other or low vacuum end to a backing pump, a plurality of jets located in series in the main casing and having substantially the same geometrical form as, and approximately co-axial with the main casing, a boiler adapted to convert the pump fluid into separate vapor streams of compounds of 70 progressively decreasing vapor pressure, means 75 for conveying the lowest vapor pressure stream

to the jet operating under the highest vacuum, means for conveying the progressively increasing vapor pressure streams to each succeeding jet operating at successively higher pressures and means for condensing the pumping vapors and returning the condensate to the boiler.

2. A condensation pump adapted to employ an organic pumping fluid which comprises in combination a main pump casing, the longitudinal axis of which is approximately horizontal, adapted to be connected at the high vacuum end to the receptacle to be evacuated and at the other or low vacuum end to a backing pump, an approximately horizontal series of jets located in the main casing and having substantially the same geometrical form as, and approximately co-axial with the main casing, an approximately horizontal boiler located in the bottom of the main pump casing and divided into a plurality of vaporizing compartments by partitions which allow pump fluid to slowly flow from one compartment to another but which substantially prevent the flow of vapor from one compartment to another, means for conveying the lowest vapor pressure stream generated in the boiler compartments to the jet operating under the highest vacuum and means for conveying the increasing vapor pressure streams generated in the other compartments to each succeeding jet operating at successively higher pressures and means for condensing the pumping vapors and directly and immediately returning substantially all of the condensate from each jet to the vaporizing compartment from which it was vaporized.

3. A condensation pump adapted to employ an organic pumping fluid which comprises in combination a main pump casing, the longitudinal axis of which is approximately horizontal, adapted to be connected at the high vacuum side to the receptacle to be evacuated and at the low vacuum side to a backing pump, an approximately horizontal series of jets located in the main casing and progressively decreasing in cross-section from the low to the high vacuum side of the pump and having substantially the same geometrical form as and approximately co-axial with the main casing, an approximately horizontal boiler located in the bottom of the main casing and divided into a plurality of vaporizing compartments by partitions which allow pump fluid to slowly flow from one compartment to another, but which prevent the flow of vapor from one compartment to another, means for conveying vapors generated in the boiler compartment nearest the high vacuum side of the pump to the jet operating at the highest vacuum and means connecting the successive boiler compartments to the successive jets operating at successively higher pressures, means for condensing the vapors issuing from each jet and for directly and immediately returning substantially all of the condensate from each jet to the boiler compartment from which it was vaporized.

4. A condensation pump adapted to employ an organic pumping fluid comprising in combination, a main pump casing, the longitudinal axis of which is approximately horizontal adapted to be connected at the high vacuum side to the receptacle to be evacuated and at the other or low vacuum side to a backing pump, a plurality of approximately annular jets located inside the main casing and adapted to pump in series, a boiling and fractionating means adapted to convert the pump fluid into separate vapor streams of compounds of decreasing vapor pressure,

means for conveying the lowest vapor pressure stream to the jet at the high vacuum end of the pump, means for conveying the progressively increasing vapor pressure streams to each jet operating at successively higher pressures and means for condensing and returning condensed fluid to the boiling and fractionating means.

5. A condensation pump adapted to employ an organic pumping fluid comprising in combination a main pump casing the longitudinal axis of which is approximately horizontal, adapted to be connected at the high vacuum side to the receptacle to be evacuated and at the other or low vacuum side to a backing pump, a plurality of approximately annular jets located inside the main casing and adapted to pump in series an approximately horizontal boiling and fractionating means located in the base of the main casing which is divided into a series of compartments 10 adapted to convert the pump fluid into separate vapor streams of compounds of progressively decreasing vapor pressure, the partitions between the compartments allowing the slow flow of pump liquid from one compartment to another, but substantially preventing the flow of vapor from one to another, means for conveying the lowest vapor pressure stream to the jet at the high vacuum side of the pump, means for conveying the progressively increasing vapor pressure streams 15 to each jet operating at successively higher pressures and means for condensing the pumping vapors and directly and immediately returning the condensate from each jet to the vaporizing compartments from which they were derived.

30 6. A vacuum pump of the condensation type adapted to employ an organic pumping fluid, comprising in combination, a main pump casing adapted to be connected at the high vacuum end to the receptacle to be evacuated and at the other or low vacuum end to a backing pump, a plurality of jets located inside the main casing and adapted to pump in series, a plurality of vaporizing compartments adapted to convert the pump fluid into separate vapor streams of compounds of 35 progressively decreasing vapor pressure, means for conveying the lowest vapor pressure stream to the jet nearest the high vacuum end of the pump, means for conveying the progressively increasing vapor pressure streams to each succeeding jet operating at successively higher pressures, condensing means and means for directly and immediately returning substantially all of the useful condensate to a vaporizing compartment the same as or contiguous to that from 40 which it was vaporized.

55 7. A vacuum pump of the condensation type adapted to employ an organic pumping fluid comprising in combination a cylindrical main pump casing, the longitudinal axis of which is approximately horizontal, adapted to be connected at the high vacuum end to the receptacle to be evacuated and at the other or low vacuum end to a backing pump, a plurality of annular jets located inside the main casing and substantially concentric therewith and adapted to pump in series, a plurality of vaporizing compartments adapted to convert the pump fluid into separate vapor streams of compounds of progressively decreasing vapor pressure, means for conveying the lowest vapor pressure stream to the jet nearest the high vacuum end of the pump, means for conveying the progressively increasing vapor pressure streams to each succeeding jet operating at successively higher pressures, condensing means for each jet and means for directly and

immediately returning substantially all of the useful condensate to the vaporizing compartment from which it was vaporized.

8. A condensation pump adapted to employ an organic pumping fluid comprising in combination, a cylindrical main pump casing the longitudinal axis of which is approximately horizontal one end of which is adapted to be connected to the receptacle to be evacuated and the other to a backing pump, a second approximately cylindrical casing of smaller diameter located inside the main casing and substantially concentric therewith, a series of annular jets located on the periphery of the second casing, an approximately horizontal boiler located in the base of the main casing and of approximately the same length as the second casing, spaced partitions in the boiler dividing it into compartments corresponding in number and position to that of the jets, the partitions allowing slow flow of liquid from one compartment to another, but substantially preventing flow of vapor from one compartment to another, means for conveying vapor from each boiler compartment to its respective jet and means for condensing the jet vapors and directly and immediately returning substantially all of the useful condensate to the same or closely adjacent boiler from which it was vaporized.

30 9. A condensation pump adapted to use an organic working fluid comprising in combination a cylindrical main pump casing, the longitudinal axis of which is approximately horizontal adapted at one end to be attached to the chamber to be evacuated and at the other end to be attached to a backing pump, a second approximately cylindrical casing located inside the first casing and approximately concentric therewith, a boiler in the base of the first casing and of approximately the same length as the second casing, a plurality of partitions inside the second casing which divide it into a plurality of approximately cylindrical compartments, corresponding partitions in the boiler which permit slow flow of pumping liquid from one boiler section to the other, but which substantially prevent passage of vapor from one section to the other, annular jets located on the outside walls of the second casing at each compartment and so located as to propel pump vapors in the direction of the backing pump, means for conveying pump vapors generated in the boiler compartments to the corresponding cylindrical compartments in the second casing and thence into the corresponding jets located on the surface thereof, means for cooling the walls of the main pump casing, and means for directly and immediately returning substantially all the pump liquid condensed on the inside walls of the main pump casing to the boiler compartments adjacent to the area of condensation.

45 10. A vacuum pump adapted to employ an organic pumping fluid comprising in combination means containing an organic fluid for producing a stream of pumping fluid vapor, a condenser, a jet through which the vapor stream flows to the condenser, a conduit connecting the chamber to be evacuated with the jet, a closed reservoir containing an organic pumping fluid, means for conveying condensed organic pumping fluid from the condenser to the reservoir and means for conveying organic pumping fluid from the reservoir to the vapor producing means at a rate such that the volume of organic fluid in the vapor produc-

ing means is small compared with the volume of the organic fluid in the reservoir.

- 5 11. A condensation pump adapted to employ an organic pumping fluid comprising in combination, a main pump casing the longitudinal axis of which is approximately horizontal, adapted to be connected at the high vacuum end to the receptacle to be evacuated and at the other or low vacuum end to a backing pump, a horizontal series of approximately annular jets located inside the main casing and approximately co-axial therewith, a boiling and fractionating means adapted to convert the pump fluid into separate vapor streams of compounds of decreasing vapor
- 10 15 pressure, means for conveying the lowest vapor

pressure stream to the jet at the high vacuum end of the pump, means for conveying the progressively increasing vapor pressure streams to each jet operating at successively higher pressures and means for condensing and returning them to the boiling and fractionating means, the jet at the high vacuum side of the pump being an umbrella type jet which is supplied with actuating vapor by a chimney characterized by the fact that the outside of the chimney in the vicinity of the jet gradually decreases in diameter in the direction in which the vapors pass from the jet. 5 10

KENNETH C. D. HICKMAN.
